ELECTRIC SIGNAL TRANSMISSION SYSTEM

John Collard, Hammersmith, London, England,
assignor to Electric & Musical Industries Lim-
ited, Hayes, Middlesex, England, a company of
Great Britain

Application October 26, 1939, Serial No. 301,324
In Great Britain October 19, 1938

15 Claims. (Cl. 178—7.3)

This invention relates to systems for the transmission of electric signals, such as television signals. It provides methods and means whereby low-frequency components differentially attenuated as compared with higher frequency components in the course of transmission may be re-established, or wherein interference components of low frequency arising in such systems may be substantially removed. It may also be employed for compensating for varying attenuation such as "fading" in signals possessing two sets of recurrent fixed-level or datum portions such as television signals.

It is well known that for the transmission and reception of television signals a particularly wide frequency band is required which includes very low frequencies and even a direct current component. It is, however, usually uneconomical to construct amplifiers to deal with the direct-current component and even the components up to two or three hundred periods per second often present difficulties. The signals at the output of an amplifier are, therefore, very often lacking in low frequency components, and some method for re-establishing them is needed in order to obtain satisfactory reproduction.

A problem very closely allied to that of such re-establishment is the one of removing unwanted low frequency components due to induction from neighbouring power circuits. Since the addition of a certain frequency component in this way is equivalent to subtracting an equal component of opposite sign, the solutions to D. C. re-establishment also serve to eliminate effects of similar low frequency that may arise by induction, for example, in neighbouring power circuits or such low-frequency effects as "tilt" in which case the present invention provides an improvement in the method of tilt elimination as described in British patent specification 490,205.

Several methods have been suggested for re-establishing direct and low-frequency components and have been described in British patent specifications 422,906, 449,242, 464,828 and 507,-239, for example, but these have only been successful up to comparatively low frequencies such as 50 cycles per second. In cases, however, where several transformers may have to be included in the circuit even components of several hundred periods per second may be so far attenuated as to require some form of re-establishment. Furthermore, unwanted frequencies up to one or two thousand periods per second may be produced in the circuit by induction from the

higher harmonics of power systems. It is evident, therefore, that some form of re-establishment is often required which is capable of operating up to frequencies of the order of 1000 cycles per second. This form of re-establishment is provided by the invention, and besides being applicable to television signals is capable of application to any signals possessing recurrent datum level periods.

According to the invention there is provided a system for the transmission of electric signals having recurrent fixed-level or datum portions in which in the course of transmission undesired changes occur in said signals comprising means for providing a corrective signal which is a substantially continuous function of time and is dependent on the simultaneously observed levels of a plurality of different datum portions and for utilising said signal to correct substantially for said undesired changes in said signals.

The invention may be carried into effect according to one aspect which may be referred to as a "delayed" or "interpolated" method, or according to another aspect which may be referred to as an "extrapolated" method.

Before, however, proceeding to give a detailed description of ways in which the invention may be carried into effect according to either of these aspects the broad basis of the invention will be explained first more fully.

Thus, as is well known, television signals consist of alternate line and synchronising signals, the line signals varying according to the picture being scanned and lasting for about 85 microseconds, the synchronising pulses lasting for about 10 microseconds and having a definite magnitude and being followed by a black-level period of about 5 microseconds duration. If upon such a waveform a single-frequency induced component is superimposed, it will be impossible during the line signal period to decide how much of the received signal is due to the induced component and how much to the actual line signal. During synchronising pulse or black-level periods, however, the matter is different and by taking the difference between the received magnitude of the pulse or height of the black-level and the magnitude that should exist it is possible to determine the amount of the induced component during that brief interval.

Existing methods of D. C. re-establishment in effect measure the discrepancy in this way and then apply a substantially constant and opposite effect during the following line signal. If the

variations in synchronising-pulse level, for example, are of such low frequency that there is practically no change in magnitude over the duration of the line signal, then the restoring effect applied in this way will successfully annul the departure that has arisen. At frequencies greater than about 50 cycles per second, however, it is inaccurate to assume that there is substantially no change over the duration of the line signal so that the method fails and for extending D. C. re-establishment to higher frequencies it is necessary to employ methods according to either aspects of the invention. These both depend on observing the difference between the true level and actual level during a number of different but preferably successive synchronising pulses or datum periods, and are thereby able to provide a restoring effect which varies over the line interval so as to supply a more exact correction.

In its simplest form the invention consists basically in effecting a delay corresponding to the interval between two synchronising pulses. The received signals are therefore passed through a delay network which is so proportioned that when one synchronising pulse has just reached the end of the network the previous pulse is just entering the network. It is thus possible to measure simultaneously the difference between the actual and correct level of these two pulses. It may be assumed that the changes in this difference are relatively low in frequency so that the difference can be considered as varying linearly over the line interval. The correction necessary in order to restore D. C. or eliminate induction over the line interval thus has a value which starts at v_1 , say, and changes linearly to v_2 , where v_1 is the value determined by observation of the synchronising pulse before the line interval and v_2 is the value determined by observation of the pulse after the line interval. This restoring signal is added to the signals as they leave the delay system.

When the whole of a line has emerged from the delay system, the synchronising pulse originally at the input of the delay has reached the output and a new pulse is just entering the input. The whole process can thus be repeated. It will be realized that this method enables higher frequencies to be handled than with earlier methods, because with the earlier system the frequency needed to be so low that there was no appreciable change in the magnitude of the required correction over the line interval; with the new method the frequency need only be low enough for the required correcting signal during the line interval to be regarded as varying linearly.

If the frequency of the induced signal exceeds about 1000 cycles per second, however, an error is introduced by assuming that its magnitude varies linearly over the line interval; by an extension of the methods of this invention, however, this error can be reduced as far as may be desired. Thus, if the signals are delayed for a time corresponding to a number of line intervals, it is possible to determine the magnitude of the required correction at each of the synchronising signals occurring within the total delayed period. In this way a series of values $v_1, v_2, v_3, \dots$, for the correcting potential are determined at uniform intervals T , where T is the time between successive synchronising pulses is thereby obtained. Now if a series of values $v_1, v_2, v_3, \dots$, of a variable are given the value of the variable at

some time t' after the time t_1 when v_1 is measured may be expressed by the series:

$$v = v_1 + (v_2 - v_1) \Delta + (v_3 - v_2) \Delta - (v_2 - v_1) \frac{\Delta(\Delta-1)}{2!} + \dots$$

where

$$\Delta = \frac{t' - t_1}{T}$$

This series is well known for use in interpolating between values given in tables. It illustrates very clearly the various approximations obtained by existing and by the new methods of D. C. re-establishment. In previous methods where only v_1 is obtained, the first term only arises; thus:

$$v = v_1$$

This equation corresponds to so-called "clamp" method of D. C. re-insertion described in the specification of British Patent No. 449,242.

10 20 In the first application of the new method described here v_2 and v_1 are obtained, so that the second term may also be used. Thus a second approximation is made according to—

$$v = v_1 + (v_2 - v_1) \Delta$$

25 30 In the further application of this new method in which $v_1, v_2, v_3, \dots$, are obtained any desired number of terms of the series may be employed giving closer and closer approximations to the true value of v .

35 In order that the invention may be more fully understood the same will now be described more particularly by way of example with reference to the accompanying drawings in which—

35 40 Figures 1, 2 and 3 show circuit arrangements whereby methods of the "delayed" kind according to the invention may be carried into effect; while

Figures 4, 5, 6 and 7 illustrate circuit arrangements wherein "extrapolated" methods are applied.

45 In a number of these arrangements it is necessary to provide some form of delay means so that the signals may be delayed by the requisite amount.

50 55 Two methods are available for producing this delay. One is to use any of the well known electrical delay networks. If this is adopted it may be necessary to correct for a large amount of distortion and attenuation by means of suitable equalisers and amplifiers, since the requirements demanded of such a network, namely, a delay time of the order of several hundred microseconds over a frequency range up to about 2 megacycles per second, are exceptional. The delay means may conveniently comprise a suitable length of television cable and its associated equipment.

60 65 The other method of obtaining the delay is to use a device allied to the electron camera in which two beams travel continually over a circular track. The first beam lays down the signals and the second picks them up again after the required interval as described in the specification of British Patent No. 471,913.

70 75 Referring to Figure 1 there is shown a functional circuit for applying the invention in its simplest form. The signals are applied at the terminals 10, 11. From there they pass through the delay network 12 which is assumed to be distortionless and free from loss, and so reach the output terminals 13, 14 by way of the condenser 15. Consider a state of affairs where one synchronising pulse is just leaving the delay network 12 while the following one is just entering

it. At this moment switches 16 and 17, which connect the terminal 10 to the terminal 11 through the condenser 18 and the battery 19 as shown in the figure, are closed. The battery 19 has an E. M. F. equal to the potential to which the terminal 10 should be raised, that is, the potential to which the terminal 10 would be raised if the synchronising pulse had its correct magnitude. If the pulse which has just reached the terminal 10 has not its correct amplitude the condenser 18 will be charged to an extent equal to the difference between the amplitude the pulse should have and that which it actually has. In the same way condenser 15, by virtue of its connection through the lead 20 and the switch 17 to the battery 19, will be charged to a corresponding extent by the pulse which has just arrived at the output of the delay network. Since the signals are taken through condenser 15 the signal amplitude at the terminals 13, 14 will consist of the signal amplitude at terminals 10, 11 together with the potential difference across the condenser 15. If the condensers 18, 15 are connected together and if it is assumed that the former is large compared with the latter then the former will eventually charge the latter to its own potential. If the connection is effected through the resistance 21 it is possible by suitably proportioning the resistance 21 in relation to condenser 18 and condenser 15 that the latter reaches substantially the potential of the former in a time equal to one line interval. Thus condenser 15 will add to the line signals a potential which starts at some value v_1 and gradually changes to some different value v_2 .

If, however, only a resistance is used to connect the condensers 18 and 15 the potential difference across the latter will change exponentially from v_1 to v_2 so that the requirement of a linear variation will not be fulfilled. This difficulty may be met by connecting an inductance 22 in series with the resistance 21. By suitably proportioning this inductance it is possible to arrange that the change in the potential difference across the condenser 15 is substantially linear.

The condensers 15 and 18 constitute in effect observing devices and enable a correcting signal to be derived which is a substantially continuous function of time and is dependent on the simultaneously observed levels of a plurality of different datum portions.

In practice the switches 16 and 19 may be replaced by valve circuits arranged to perform the same operations. Various forms of valve switches have been proposed in connection with so called "clamp" D. C. re-establishment, and in particular the six-diode switch described in British Patent No. 512,109 may be applied here.

Figure 2 shows an alternative arrangement for obtaining a linear restoring potential. As before there are the input and output terminals 10, 11 and 13, 14 respectively connected through the delay network 12, the condenser 15 being connected in the lead from the delay network to the terminal 13. The terminal 10 and the terminal of condenser 15 connected to the output of the delay network are connected respectively through the switches 23, 24 and the condensers 25, 26 to ground, these condensers forming the observing devices in this example of the invention. The plates of these condensers not connected to earth are taken to the control grids 27, 28 of the valves 29 and 30 respectively. These valves have a large resistance 31 connected in their common-cathode circuit, so that the poten-

tial of either anode 32, 33 is proportional to the difference of the potentials on the two grids. The anode 33 is connected through the condenser 34 and the resistance 35 to the output terminal 13, the condenser 34 being of large capacity compared with that of condenser 15. The output terminal 13 is connected through the switch 36 to the battery 37 and through the battery to ground. At the moment one synchronising pulse reaches the end of the delay network 12 and the following one is entering the beginning, the switches 23, 24 and 36 are closed. Condenser 25 thus becomes charged to a value corresponding to v_2 , say, and condenser 26 some other value corresponding to v_1 . The potential change arising at the anode 33 of valve 30 is proportional to $v_2 - v_1$.

Accordingly, the charging current flowing from valve 30 through the condenser 34 and the resistance 35 to condenser 15 is also proportional to $v_2 - v_1$. At the beginning of the line the condenser 15 has a potential difference between its terminals equal to v_1 due to the charge obtained from the battery 37 through the switch 36. By suitably adjusting the magnitude of the resistance 35 it is possible to arrange that the steady charging current from valve 30 shall increase the potential difference across condenser 15 to v_2 at the end of the line. Thus condenser 15 supplies the correct restoring potential starting at v_1 and increasing linearly to v_2 . In order that the current from valve 30 shall be independent of the potential changes of condenser 15 during the line interval, it is necessary to arrange that the potential changes on the anode of valve 30, which produce the charging current, shall be large compared to the changes occurring in condenser 15. The gain of valves 29 and 30 is therefore made large and the resistance 35 is also made large.

It was pointed out that a better approximation to the correct restoring potential could be obtained by observing a larger number of synchronising pulses. If three pulses are observed the expression for the restoring potential is

$$v = v_1 + (v_2 - v_1) \Delta + \{ (v_2 - v_2) - (v_2 - v_1) \} \frac{\Delta(\Delta - 1)}{2}$$

The circuit corresponding to this equation is shown in Figure 3. The arrangement is similar to that of Figure 2 except that two delay networks 12 and 12' are used, there being connected to these delay networks in manner precisely similar to that of Figure 2, the pairs of valves 29, 30 and 29', 30' respectively. In similar manner also the anodes 33 and 33' of the valves 30 and 33' are taken through series resistance-capacity circuits 34, 35 and 34', 35' respectively to the terminal 13 with which is associated as before the switch 36 and battery 37.

The anodes 33 and 33' are, however, also connected through series resistance-capacity circuits 38, 39 and 38', 39' to the grid 40 of the valve 41 whose cathode is earthed. Between the grid 40 and earth there is connected the condenser 42 and across this condenser is arranged the switch 43 and battery 44 in series. The anode 45 of valve 41 is connected through the condenser 46 and resistance 47 to the terminal 13.

In order to relate the above expression to this circuit arrangement it may be written in the re-arranged form:

$$v = v_1 + (v_2 - v_1) \frac{3\Delta}{2} - (v_3 - v_2) \frac{\Delta}{2} - \{ (v_2 - v_1) - (v_2 - v_2) \} \frac{\Delta^2}{2}$$

The term v_1 is obtained by closing switch 36 and charging condenser 15 from battery 37. The term $(v_2 - v_1) \frac{3\Delta}{2}$ is obtained from the anode of valve 33', and the term $-(v_3 - v_2) \frac{\Delta}{2}$ is obtained from valve 33, the pairs of valves 29, 30 and 29', 30' operating in the same way as in Figure 2. The two resistances 35 and 35' are adjusted in the proportion of three to one and the gain of all four valves is arranged to be substantially the same so that the charging currents from valves 30' and 30 are in the correct ratio. The anodes of these valves are also connected to condenser 42 through large condensers and resistances. Hence the total charging current into condenser 42 is proportional to $(v_2 - v_1) - (v_3 - v_2)$. The potential difference across the condenser 42 is thus equal to $\{(v_2 - v_1) - (v_3 - v_2)\}\Delta$. Since the grid of valve 41 is connected to condenser 42 the anode voltage of valve 41 is therefore proportional to $-(v_2 - v_1) - (v_3 - v_2)\Delta$. Also as the anode of valve 41 is connected to condenser 15 through the large condenser 46 and resistance 47, condenser 15 is therefore supplied with a charging current proportional to $-(v_2 - v_1) - (v_3 - v_2)\Delta$. The potential difference built up across condenser 15 due to this current is accordingly proportional to $-(v_2 - v_1) - (v_3 - v_2)\Delta^2$. The total potential difference across condenser 15 is thus made to vary in accordance with the full expression given above for v and is thus correct to a second order of approximation throughout the line interval. Since the process is required to start fresh at the end of each line the switch 43 is provided to short circuit condenser 42 and so prepare it for the new charge. The battery 44 is used to avoid short circuiting the grid of valve 41 to earth.

The steps involved in the extension of this scheme to include still further terms will be obvious from the above.

It will be appreciated from the foregoing illustrations that the chief feature of the invention as carried into effect according to "delayed" methods is that the restoring potential is determined from observations made on synchronising pulses before and after the line interval for which the restoring potential is to be used. This necessitates the delaying of the line signals, which is a disadvantage as it is comparatively expensive to construct a delay system to give a uniform delay up to 2 or 3 megacycles. To avoid this difficulty "extrapolated" methods of re-establishment which will now be illustrated, may be used. In these a number of successive synchronising pulses are observed and the observations are used to set up the restoring potential for the line interval following immediately after the last observed synchronising pulse. Thus no delay of the line signals is required. In order to be able to observe simultaneously a number of synchronising pulses, these may be passed through a delay system tapped at suitable points as in the case of the delay networks used for delaying the line signals in "delayed" re-establishment. Since the delay network has now only to deal with synchronising pulses and not line signals it may possess characteristics of much less perfect form with a resultant economy. Furthermore, as will be shown later, there is a method of dispensing with the delay network altogether. Hence "extrapolated" methods of re-establishment are considerably more simple to effect than "delayed" methods. However, "extrapolated" re-establish-

ment has the disadvantage that it is not so accurate as the "delayed" method. This follows naturally from the fact that the "delayed" method depends upon interpolating between certain values while the other method operates by extrapolating beyond the last observed point.

The first stage of the "extrapolated" method is the same as the original "clamp" D. C. re-establishment (see British Patent No. 449,242). It consists of measuring the restoring potential v_1 for the synchronising pulse immediately preceding the line interval and then applying a constant potential of this magnitude throughout the following line interval. This assumes, of course, that the restoring potential remains constant during the line interval, which is only true for very low frequencies. If the restoring potential is given by $v = A \sin \omega t$, then the maximum error produced by applying the constant voltage v_1 is:

$$e_1 = 100 \sin \omega T$$

per cent, where T is the time interval of one line

The second stage of approximation is to observe the restoring potentials v_1 and v_2 during two successive synchronizing pulses and then apply a restoring potential of:

$$v = v_2 + (v_2 - v_1) \frac{t}{T}$$

where t is the time interval after the last observed synchronising pulse and varies from zero to T . This is equivalent to assuming that the mean slope of the restoring potential during the line when the correction is being applied, is the same as the mean slope in the previous line interval. This assumption is valid up to somewhat higher frequencies than the previous assumption and is therefore an improvement upon "clamp" D. C. re-establishment. The maximum error per cent is:

$$e_2 = 400 \sin^2 \frac{\omega T}{2}$$

A yet closer approximation is obtained by observing three successive synchronising pulses, thus deriving three consecutive correcting potentials v_1 , v_2 and v_3 . The restoring potential that can then be applied is:

$$v = v_3 + (v_3 - v_2) \frac{t}{T} + (v_2 - v_1) \frac{t}{T}$$

The corresponding maximum error is expressed per cent by:

$$e_3 = 400 \sin^2 \frac{\omega T}{2} \sin \omega T$$

showing the extent to which the approximation is better than the previous one.

The process can, of course, be carried still further by observing additional synchronising pulses. The maximum errors for the first three approximations given above are tabulated below for various frequencies.

Frequency, cycles per second	e_1	Maximum error e_2	Percent e_3
50	3.1	0.1	-----
100	6.3	0.4	-----
200	12.6	1.6	0.2
500	30.9	9.8	3.0
1,000	55.8	38.3	23.6
2,000	95.1	138.0	163.3

The column e_1 corresponds to "clamp" D. C. re-establishment and it will thus be seen that

the closer approximations give considerably better results except at the higher frequencies.

It will be noticed that the variable terms so far considered have all been linear in t , so that the resultant restoring potential varies as a straight line throughout the line interval. It will be obvious that by taking terms proportional to

$$\left(\frac{t}{T}\right)^2$$

the restoring potential can be caused to curve during the line interval as was done in "delayed" D. C. re-establishment.

Figure 4 shows a circuit arrangement for applying the second approximation of the "extrapolated" method, i. e., for producing a restoring potential of form

$$v_2 - (v_2 - v_1) \frac{t}{T}$$

As in previous circuit arrangements there are the input and output pairs of terminals 10, 11 and 13, 14, but the condenser 15 is connected directly between the terminals 10 and 13 without the intervening delay network. However, the input of the delay network 48 is connected across the input terminals 10 and 11, its output being terminated in the resistance 49. From the input and output of this delay network connections are made through the switches 50 and 51 to the observing condensers 52 and 53 respectively and through these condensers to earth. From the condensers connections are further made to the grids 54 and 55 of a pair of valves 56 and 57 having a large cathode impedance 58. At the anode 59 of valve 56 there accordingly appears a potential proportional to $v_2 - v_1$ as will be appreciated from previous explanations. This anode is taken through the large condenser and resistance 60 and 61 respectively to the terminal 13, which, as before, is connected through the switch 36 to the battery 37 and thence to earth.

At the instant when a given synchronising pulse reaches the beginning of the delay network 48 the switch 36 is closed, thus charging condenser 15 to an extent corresponding to v_2 . Switches 50 and 51 are also closed so that condenser 52 receives a charge depending on v_2 while condenser 53 which is connected to the far end of the delay network 48, receives a charge depending on v_1 . The delay in this case is, of course, equal to the interval between two consecutive synchronising pulses. The two valves 56, 57 as in the "delayed" D. C. re-establishment, supply a charging current to condenser 15 through condenser 60 and resistance 61 proportional to $v_2 - v_1$, and therefore provide the term

$$(v_2 - v_1) \frac{t}{T}$$

To apply this method to the third approximation, i. e., using a restoring voltage of:

$$v_3 = (v_3 - v_2) \frac{t}{T} - \{ (v_3 - v_2) - (v_2 - v_1) \} \frac{t}{T}$$

merely requires an obvious extension of the circuit of Figure 4 using two delay networks of one line interval delay each and two pairs of valves each like the pair 56 and 57.

Since this method depends on observations taken only on synchronising pulses occurring before the line interval for which the restoring potential is required it is possible to dispense altogether with the delay system. This provides a considerable gain in simplicity. Figure 5

shows diagrammatically how this may be carried out.

The terminals 10 and 13 are joined through the condenser 15, and terminal 13 is connected to earth through the switch 36 and battery 37 in series as in Figure 4. Terminal 10 is however, taken to one of three contacts 62, 63, 64 namely 62. Associated with these contacts is a rotating system of three observing condensers 65, 66, 67 having a clockwise motion and being connected in a star arrangement with the central point earthed. The free plates are periodically brought into contact with the points 62, 63, 64 by means of brushes which are indicated by arrows. The contacts 62 and 63 are connected to the device 68 which comprises a pair of valves arranged in exactly the same manner, for example, as the valves 56 and 57 in Figure 4 and performing the same function. From the output of this device connection is made by a large condenser and resistance, 70 and 71 respectively, to terminal 13. The contacts 63 and 64 are connected to the terminal 13 in a precisely similar way, namely, through the device 69, similar to the device 68, and through the condenser 72 and resistance 73.

When the first synchronising pulse reaches the condenser 15 the switch 36 is closed so that condenser 15 is charged to a potential v_1 . Condenser 67 also receives a charge depending on v_1 . Just before the next synchronising pulse reaches condenser 15 the condenser assembly is rotated through 120° so that now condenser 67 is connected to contact 63, condenser 66 to contact 63 and condenser 65 to contact 62. Since condenser 67 still carries its charge it will raise contact 63 to a potential depending on v_1 . When the second synchronising pulse reaches condenser 15 the switch 36 is closed again so that condenser 15 now becomes charged to a potential v_2 . Condenser 65 also receives a charge depending on v_2 . Just before the third synchronising pulse reaches condenser 15, the condenser assembly is rotated again through 120°. When the third pulse arrives the switch 36 is closed again so that condenser 15 is now charged to a potential v_3 . Condenser 66 also receives a charge depending on v_3 , and condenser 65 retains a charge depending on v_2 . The position now is that condenser 67 has a charge depending on v_1 and is connected to contact 64, condenser 66 has a charge depending on v_3 and is connected to contact 62, and condenser 65 has a charge depending on v_2 and is connected to contact 63. Since the device 68 is connected to contacts 62 and 63 a charging current is therefore given to condenser 15 proportional to $v_3 - v_2$. By reason of the similar device 69 there is also given a charging current to condenser 15 proportional to $v_2 - v_1$. Hence by suitably adjusting the gains of the two devices 68 and 69 and the resistances 71, 73, it can be arranged as previously described that the potential of condenser 15 has the correct value throughout the line interval. For subsequent synchronising pulses, the series of operations continues in a similar fashion.

A way in which this scheme may be put into practice without the use of moving mechanical parts is shown in Figure 6. This arrangement is identical with that of Figure 5 except that the contacts 62, 63, 64 are replaced by leads having the same reference numbers, the condensers 65, 66 and 67 are now fixed and the brushes are replaced by the array of switches shown. Switches 75, 76, 77 are capable of connecting the condens-

ers 65, 66, 67 respectively to the lead 62. Switches 78, 79, 80 perform a similar function with respect to the lead 63 as do switches 81, 82, 83 with respect to lead 64. Switch 74 connects terminals 10 to lead 62. The various switches, would, of course, consist of suitable valve circuits as already discussed.

When the first synchronising pulse reaches condenser 15 the switches 74, 36 and 78 are closed. This charges condenser 15 to the potential v_1 and gives condenser 65 a charge depending on the same potential. Before the following line signal starts switch 74 is opened. At the second synchronising pulse the switches 74, 36, 16 and 78 are closed, 74 being opened again before the line signal begins. Condenser 66 then has a charge depending on the potential v_2 and condenser 65 retains its charge which depends on v_1 . At the third synchronising pulse the switches 74, 36, 77, 79 and 81 are closed, 74 being opened before the line signal begins. This leaves condenser 65 with a charge depending on v_1 , condenser 66 with a charge depending on v_2 , condenser 67 with a charge depending on v_3 and condenser 15 with a potential equal to v_3 . Also device 68 is connected to condensers 67 and 66 and therefore gives a charging current to condenser 15 proportional to $v_3 - v_2$, while device 69 is connected to condensers 66 and 65 and therefore gives a charging current to condenser 15 proportional to $v_2 - v_1$. Thus the correct potential difference across condenser 15 may be maintained throughout the line interval, and for subsequent synchronising pulses, the series of operations is continued.

The disadvantage of the above scheme is its obvious cumbrousness and a greatly simplified arrangement is shown in Figure 7. The condensers 65, 66 and 67, as previously, each have one plate connected to earth but the opposite plates are connected permanently to the leads, 62, 63, 64 respectively. The previous array of switches is replaced by the three switches 84, 85, 86 and the two cathode follower valves 87 and 88 having cathode resistances 93 and 94. Switch 84 connects terminal 10 to the unearthing plate of condenser 65 and the grid 89 of valve 87. Switch 85 connects the cathode 91 of valve 87 to the unearthing plate of condenser 66 and the grid 90 of valve 88. Similarly switch 86 connects the cathode 92 of valve 88 to the unearthing plate of condenser 67.

At the first synchronising signal switch 84 is closed and then opened again; this gives a charge to condenser 65 depending on the potential v_1 . As in previous cases switch 36 is used to give condenser 15 the correct potential v_1, v_2, v_3 , etc., as the case may be, and its use, therefore, need not be dealt with again. When the second synchronising pulse arrives switch 85 is first closed. Since valve 87 is a cathode follower this causes condenser 66 to be charged to substantially the same voltage as condenser 65. Switch 85 is then opened, and switch 84 is closed for a short time and opened again, causing condenser 65 to have a charge depending on v_2 . Hence condenser 66 now has a charge depending on v_1 and condenser 65 one depending on v_2 . When the next pulse arrives switch 86 is first closed causing condenser 67 to receive a charge depending on v_1 . Switch 86 is then opened and switch 85 is closed, causing condenser 66 to receive a charge depending on v_2 . Switch 85 is then opened, and switch 84 is closed and opened again, causing condenser 65 to receive a charge depending on v_3 . Thus con-

denser 67 has a charge depending on v_1 , condenser 66 a charge depending on v_2 and condenser 65 a charge depending on v_3 . Thus the same state of affairs is arrived at as with the previous and more complicated switching scheme.

It will have been appreciated that the series of switching operations requires to be completed before the synchronising pulse is over and this can be effected by passing the pulse down a delay network. Across this network are bridged three valves causing the switches 84, 85, 86 to operate. As the pulse reaches each valve the corresponding switch is caused to operate. By suitably selecting the tapping points the various operations can be made to take place at the correct times. The method of arranging such a delay network and switching device has been already described in connection with "clamp" D. C. re-establishment for example in British patent specification No. 449,242.

The arrangements described, it will have been noticed, have all been based on observations on the magnitude of synchronising pulses. As, however, stated earlier an alternative method is to observe the level of the short black interval which follows each synchronising pulse and precedes the line signal. The previous methods all apply equally well to this case except that, of course, the various switches must be closed during the black interval instead of during the synchronising pulse interval.

It is possible in some instances to combine the methods of "delayed" and "extrapolated" re-establishment with advantage. For example, Figure 3 shows a method of applying "delayed" D. C. re-establishment in which three successive synchronising pulses are observed. These values are obtained by two delay networks each giving a delay equal to the interval between synchronising pulses. If v_1, v_2 and v_3 are the three restoring potentials observed then v_2 is obtained by means of one delay network and v_3 by means of two delay networks. The restoring potential derived from these is applied to correct in the line interval between v_1 and v_2 . It is possible, however, instead of observing the potential v_3 to observe and store the synchronising pulse prior to that giving the potential v_1 , thereby deriving a correcting potential v_3 say. This can be done by using the methods described for "extrapolated" D. C. re-establishment. Then the potentials v_0, v_1 and v_2 can be used to establish the restoring potential for the line interval between the pulses corresponding to v_1 and v_2 , instead of employing the potentials v_1, v_2 and v_3 as previously. The advantage of this is that the second delay network is now not needed. In "extrapolated" methods the restoring potential may be applied in any part of the transmission path along which the signals are transmitted either before or after the point from which the correcting signal is derived.

The invention may be used in overcoming the effect of fading in television transmission (see British Patent No. 458,585) by employing the methods of the invention to develop a gain-control potential which depends on a plurality of datum levels simultaneously observed and varies continuously, or substantially so, in like manner to the D. C. restoring potential as described above, this development of a gain-control potential, of course, depending upon the previous re-establishment in the signals of the direct and slowly varying components by means of another

set of datum levels in the signals different from those to be used in deriving the gain-control potential. The television waveform possesses two full sets of datum levels; namely the peaks of synchronizing signals constitutes one, the black level datum portions another. For D. C. re-inserting, of course, and interference elimination either may be used as desired as already stated; this still applies when a gain-control potential is likely to be developed.

I claim:

1. In a television system having video signals combined with interspersed synchronizing impulses and in which direct current and low frequency components of the video signals are suppressed which combined signals and impulses are subjected to distortion in transmission, the method of correcting signals representative of the suppressed components derived from the synchronizing signals at a receiving point which includes the steps of receiving the combined signals and impulses, comparing the received synchronizing impulses with each other, deriving energy representative of the difference of the compared impulses, and adding progressively varying energy to the received signals during the time interval between the synchronizing impulses, the variation of the energy being between the limits of zero and a maximum value proportional to the difference between the compared impulses.

2. In a television system having video signals combined with interspersed synchronizing impulses and in which direct current and low frequency components of the video current and low frequency components of the video signals are suppressed which combined signals and impulses are subjected to distortion in transmission, the method of correcting signals representative of the suppressed components derived from the synchronizing signals at a receiving point which includes the steps of comparing the received successive synchronizing impulses with each other, deriving energy representative of the difference of the compared impulses, and adding progressively varying energy to the received signals during the time interval between the synchronizing impulses, the variation of the energy being between the limits of zero and a maximum value proportional to the difference between the compared impulses.

3. In a television system having video signals combined with interspersed synchronizing impulses and in which direct current and low frequency components of the video current and low frequency components of the video signals are suppressed which combined signals and impulses are subjected to distortion in transmission, the method of correcting signals representative of the suppressed components derived from the synchronizing signals at a receiving point which includes the steps of comparing the received successive groups of synchronizing impulses with each other, deriving energy representative of the difference of the compared impulses, and adding progressively varying energy to the received signals during the time interval between the synchronizing impulses, the variation of the energy being between the limits of zero and a maximum value proportional to the difference between the compared impulses.

4. In a television system having video signals combined with interspersed synchronizing impulses and in which direct current and low frequency components of the video signals are suppressed which combined signals and impulses

are subjected to distortion in transmission, the method of correcting signals representative of the suppressed components derived from the synchronizing signals at a receiving point which includes the steps of receiving the combined signals and impulses, delaying the combined signals and impulses, comparing delayed synchronizing impulses with undelayed synchronizing impulses, deriving energy representative of the difference of the compared impulses, and adding progressively varying energy to the received signals during the time interval between the synchronizing impulses, the variation of the energy being between the limits of zero and a maximum value proportional to the difference between the compared impulses.

5. In a television system having video signals combined with interspersed synchronizing impulses and in which direct current and low frequency components of the video signals are suppressed which combined signals and impulses are subjected to distortion in transmission, the method of correcting signals representative of the suppressed components derived from the synchronizing signals at a receiving point, which includes the steps of receiving the combined signals and impulses, comparing the received synchronizing impulses with each other, deriving potential increasing linearly with respect to time between the limits of zero and a maximum value in proportion to the difference of the compared impulses, and adding said derived potential to said received combined signal and impulses.

6. In a television system having video signals combined with interspersed synchronizing impulses and in which direct current and low frequency components of the video signals are suppressed which combined signals and impulses are subjected to distortion in transmission, the method of correcting signals representative of the suppressed components derived from the synchronizing signals at a receiving point which includes the steps of receiving the combined signals and impulses, comparing the received synchronizing impulses, deriving potential increasing parabolically with respect to time between the limits of zero and a maximum value in proportion to the difference of the compared impulses, and adding said derived potential to said received combined signal and impulses.

7. In a television system having video signals combined with interspersed synchronizing impulses and in which direct current and low frequency components of the video signals are suppressed which combined signals and impulses are subjected to distortion in transmission, the method of correcting signals representative of the suppressed components derived from the synchronizing signals at a receiving point which includes the steps of receiving the combined signals and impulses, delaying the received combined signals and impulses, comparing delayed groups of synchronizing impulses with undelayed groups of synchronizing impulses, deriving energy representative of the difference of the compared impulses, and adding progressively varying energy to the received signals during the time interval between the synchronizing impulses, the variation of the energy being between the limits of zero and a maximum value proportional to the difference between the compared impulses.

8. A direct current insertion television system comprising means to receive video signals combined with interspersed synchronizing impulses

in which direct current and low frequency components of the video signal are suppressed which combined signals and impulses are subjected to distortion in transmission, means for comparing the received synchronizing impulses with each other, means for deriving energy representative of the difference of the compared impulses, and means for adding progressively varying energy to the received signals during the time interval between the synchronizing impulses, the variation of the energy being between the limits of zero and a maximum value proportional to the difference between the compared impulses.

9. A direct current insertion television system comprising means to receive video signals combined with interspersed synchronizing impulses in which direct current and low frequency components of the video signals are suppressed which combined signals and impulses are subjected to distortion in transmission, means for comparing the received successive synchronizing impulses with each other, means for deriving energy representative of the difference of the compared impulses, and means for adding progressively varying energy to the received signals during the time interval between the synchronizing impulses, the variation of the energy being between the limits of zero and a maximum value proportional to the difference between the compared impulses.

10. A direct current insertion television system comprising means to receive video signals combined with interspersed synchronizing impulses in which direct current and low frequency components of the video signals are suppressed which combined signals and impulses are subjected to distortion in transmission, means for comparing the received successive groups of synchronizing impulses with each other, means for deriving energy representative of the difference of the compared impulses and means for adding progressively varying energy to the received signals during the time interval between the synchronizing impulses, the variation of the energy being between the limits of zero and a maximum value proportional to the difference between the compared impulses.

11. A direct current insertion television system comprising means to receive video signals combined with interspersed synchronizing impulses in which direct current and low frequency components of the video signals are suppressed which combined signals and impulses are subjected to distortion in transmission, means for delaying the combined signals and impulses, means for comparing delayed synchronizing impulses with undelayed synchronizing impulses, means for deriving energy representative of the difference of the compared impulses, and means for adding progressively varying energy to the received signals during the time interval between the synchronizing impulses, the variation of the energy being between the limits of zero and a maximum value proportional to the difference between the compared impulses.

12. A direct current insertion television system comprising means to receive video signals combined with interspersed synchronizing impulses in which direct current and low frequency components of the video signals are suppressed which combined signals and impulses are subjected to distortion in transmission, means for comparing the received synchronizing impulses with each other, means for deriving potential increasing linearly with respect to time in proportion to the difference of the compared impulses, and means for adding said derived potential to said received combined signal and impulses.

13. A direct current insertion television system comprising means to receive video signals combined with interspersed synchronizing impulses in which direct current and low frequency components of the video signals are suppressed which combined signals and impulses are subjected to distortion in transmission, means for comparing the received synchronizing impulses with each other, means for deriving potential increasing parabolically with respect to time in proportion to the difference of the compared impulses and means for adding said derived potential to said received combined signal and impulses.

14. A direct current insertion television system comprising means to receive video signals combined with interspersed synchronizing impulses in which direct current and low frequency components of the video signals are suppressed which combined signals and impulses are subjected to distortion in transmission, means for delaying the combined signals and impulses, means for comparing delayed groups of synchronizing impulses with undelayed groups of synchronizing impulses, means for deriving energy representative of the difference of the compared impulses, and means for adding progressively varying energy to the received signals during the time interval between the synchronizing impulses, the variation of the energy being between the limits of zero and a maximum value proportional to the difference between the compared impulses.

15. A direct current insertion television system comprising means to receive video signals combined with interspersed synchronizing impulses in which direct current and low frequency components of the video signals are suppressed which combined signals and impulses are subjected to distortion in transmission, & delay network fed by said received signals, said delay network having an output circuit, thermionic means connected across said output circuit, means common to both named thermionic means for deriving a potential proportional to the difference between the received energy and the energy of the output circuit, and means connected between said second named thermionic means and said output means for adding to said output circuit energy representative of the difference derived across said common means.
